Primary Examiner — Darlington Ly*Assistant Examiner* — Katherine A Holbrow(74) *Attorney, Agent, or Firm* — Middleton Reutlinger(57) **CLAIM**

The ornamental design for a display screen or portion thereof with graphical user interface, as shown and described.

DESCRIPTION

The FIGURE is a front view of a display screen or portion thereof with graphical user interface, showing the new design.

The broken lines illustrate a display screen or portion thereof with graphical user interface, and form no part of the claimed design.

1 Claim, 1 Drawing Sheet(56)
